US00D736224S

(12) **United States Design Patent**
Everingham et al.

(10) **Patent No.:** **US D736,224 S**
(45) **Date of Patent:** **** Aug. 11, 2015**

(54) **PORTION OF A DISPLAY SCREEN WITH A GRAPHICAL USER INTERFACE**

(75) Inventors: **James R. Everingham**, Santa Cruz, CA (US); **Sarah Jane Waterson**, Fort Collins, CO (US)

(73) Assignee: **Yahoo! Inc.**, Sunnyvale, CA (US)

(**) Term: **14 Years**

(21) Appl. No.: **29/403,731**

(22) Filed: **Oct. 10, 2011**

(51) LOC (10) Cl. **14-04**

(52) U.S. Cl.

USPC **D14/486**

(57) **CLAIM**

The ornamental design for portion of a display screen with a graphical user interface, as shown and described.

DESCRIPTION

The FIGURE is a front view of a portion of a display screen with a graphical user interface showing the new design. The dashed lines showing text and images form no part of the claimed design. Said dashed lines, dashed image, and text are presented only for environmental purposes.
